UNITED STATES PATENT OFFICE.

RICHARD H. MORROW AND JAMES MORROW, OF WAUKEGAN, ILLINOIS.

INTERNAL-COMBUSTION MOTOR.

1,084,749.

Specification of Letters Patent.

Patented Jan. 20, 1914.

Application filed March 17, 1910. Serial No. 549,966.

To all whom it may concern:

Be it known that we, RICHARD H. MORROW and JAMES MORROW, citizens of the United States, residing at Waukegan, county of

5 Lake, and State of Illinois, have invented certain new and useful Improvements in Internal-Combustion Motors, of which the following is a specification.

This invention relates to internal combustion motors and has for its primary object 10 to provide an improved combined valve mechanism and starting device.

One of the objects of this invention is to provide an improved construction, combination 15 and arrangement of parts in valve mechanism for internal combustion engines.

More specifically, another object is to provide an improved construction, combination and arrangement of parts in valve mechanism for internal combustion engines having 20 duplex pistons.

Another object is to provide an improved starting device which will be operative through and automatically governed by the 25 valve mechanism constructed in accordance with the principles of the present invention.

Other and further objects will appear in the specification and be more specifically pointed out in the claims, reference being 30 had to the accompanying drawings exemplifying the invention.

In the drawings, Figure 1 is a front elevation of one embodiment of our invention. Fig. 2 is a section on the broken line II—II 35 of Fig. 3, showing the valve housing and valve with the passages for gaseous mixtures connecting said housing with the charging and combustion chambers. Fig. 3 is a section on the line III—III, Fig. 2. Fig. 4 is 40 a section on the line IV—IV, Fig. 2. Fig. 5 is a section on the line V—V, Fig. 2. Fig. 6 is a section on the line VI—VI, Fig. 2. Fig. 7 is a section on the line VII—VII, Fig. 2. Fig. 8 is a section on the line 45 VIII—VIII, Fig. 2. Fig. 9 is a transverse section of the valve mechanism in a modification of our invention, said section being taken on a line corresponding to the line III—III, Fig. 2. Fig. 10 is the same section 50 as Fig. 9 showing the valve in a different position. Fig. 11 is a transverse section on the line XI—XI, Fig. 2. Fig. 12 is a section on the line XII—XII, Fig. 2. Fig. 13 is a section on the line XIII—XIII, Fig. 2. 55 Fig. 14 is a transverse section through one of the engines of another modified form of

the invention, said section corresponding to the section shown in Fig. 3. Fig. 15 is a section on the line XV—XV, Fig. 10, parts being broken away.

Referring more particularly to the embodiment shown in the drawings and first of all to that embodiment shown in Figs. 1 to 7 inclusive, and 10 to 13 inclusive, while the invention has been exemplified in its application to an internal combustion engine embodying three combustion cylinders, said invention is equally applicable to an engine having any desired number of cylinders. The cylinders 1, 2, and 3 are preferably 60 formed in a single casing, each of said cylinders being provided below with an enlarged cylindrical chamber 4, as shown in Fig. 3. Reciprocably mounted in each cylinder is a duplex piston comprising the 65 smaller piston body 5 and the larger piston body 6 there below. The smaller piston 5 is a power developing piston while the larger piston 6 is adapted by its reciprocation in the enlarged cylindrical chamber 4, which hereinafter will be termed the charging or compression cylinder or chamber, to first draw in a gaseous mixture and then to force said mixture in a manner hereinafter to be pointed out into the combustion chamber. 70 Each piston 5 is connected by a connecting rod 7 with a crank 8, the cranks of the several engines being disposed at equally spaced angles about an engine shaft 9. The engine casing is preferably formed in two casings, 75 the upper including the engine cylinders and the lower including the crank casing for the three engines. Preferably integrally formed on the lateral wall of the lower crank casing 80 is a valve housing 11, said valve housing 85 in turn being provided with a protuberant portion 12 provided with a manifold valve chamber for a purpose to be hereinafter pointed out. Without the engine cylinders and preferably adjacent to the end cylinder 90 1 is a chamber 13 for storing some of the gaseous products of combustion. A pipe 95 connects the storage chamber 13 with the manifold valve housing 12 and three pipes 100 15, 16 and 17 connect the manifold valve housing 12 with the cylinders 1, 2 and 3 respectively, thus constituting a starting device for the engine. The interior valve mechanism of the manifold valve housing 12 will be hereinafter specifically described. 105 The storage chamber 13 may be connected 110 to the upper end of any or all cylinders, but

- as shown on the drawing is connected to the cylinder 1 by a pipe 18 which conducts some of the gaseous products of combustion to the storage chamber 13 at every explosion in the engine cylinder 1, provided that the pressure in the storage chamber 13 is not sufficient to prevent the actuation of a check valve 19 in the pipe 18. Interposed in the pipe 14 between the storage chamber 13 and the manifold 12 is a valve 20, of any suitable construction, whereby the storage chamber may be shut off from the manifold 12 or placed in connection therewith to start the engine.
- 15 Referring now more especially to Fig. 2, the valve housing 11 preferably extends across all three of the engine cylinders 1, 2 and 3, said housing comprising a receiving chamber 21 into which a gaseous mixture may be introduced through an inlet 22 which may connect with the carburetor, a reservoir 23 for compressed gaseous mixture and a valve chamber 24. Within the valve chamber 24, which is preferably tubular in form, is rotatably mounted a cylindrical valve 25, said valve being preferably mounted in ball bearings at 26, 27 and geared by means of gears 28, 29 to the engine shaft 9. The valve chamber 24 is provided with a port leading to the charging chamber and the combustion chamber of each engine, ports leading to the charging chamber in each instance leading directly from the valve chamber 24 by means of ducts 30, 31 and 32, said ducts being provided with ports 33, 34 and 35 into said charging cylinders. The ports leading to the combustion chambers on the other hand are connected by way of the reservoir 23 and openings 36, 37 and 38 with ducts 39, 40 and 41, which last said ducts are adapted at certain positions of the piston to discharge into the respective combustion chambers through the ports 42, 43 and 44. The valve chamber 24 is also provided with ports 45, 46 and 47 connecting with the inlet chamber 21. Cooperatively arranged in the valve 25 are a plurality of port openings 48, 49 (see Fig. 3), 50 (see Fig. 4), 55, 56 (see Fig. 5), 57 (see Fig. 6), 58, 59 (see Fig. 7) and 60 (see Fig. 8). These ports in the valve are so arranged and related to the ports in the valve chamber as to bring the charging cylinder into communication with the inlet chamber during the outward movement of the piston in the cylinder. Thus by reference to Fig. 3, it will be seen that as the piston 5 descends, there is a vacuum produced in the chamber 4 and as the port 49 in the valve 25 registers with the duct 30 and the port 50 in the valve 25 registers with the port 45 in the valve chamber 25 (see Fig. 4), the gaseous mixture rushes from the inlet chamber 21 through the valve and into the chamber 4 to fill said chamber. As shown in Figs. 2 and

3, the inlet port 42 into the combustion chamber is located at a relatively low point so that the charge cannot be admitted into the cylinder before the port 42 is uncovered by the piston 5. By the time, however, that the piston 5 has reached its lowermost position, the charging chamber 4 has been completely filled with gaseous mixture and the port 42 is fully opened.

As indicated in Fig. 3, the valve 25 is geared to the engine shaft 9 with the ratio of one to one, so that at each revolution of the engine shaft 9, the contents of the charging chamber 4 are compressed and forced through the valve into the compression reservoir 23 which takes place when the port 48 has revolved 180 degrees from its position shown in Fig. 3 to register with the duct 30 when the port 50 of the valve will be found to register with the port leading to the compression reservoir 23. It will thus be seen that the compression reservoir 23 is kept supplied by each of the three engines with compressed gaseous mixture. As the piston 5 nears the lower end of its stroke the port 42, being uncovered, permits a rush of the compressed gaseous mixture into the combustion chamber, said chamber being scavenged through the exhaust passage 61. The arrangement is such that each cylinder is simultaneously scavenged and charged for every revolution, the charge being compressed by the upward movement of the piston 5 to be exploded by a sparking device 62. As each of the engines operates in the same manner, it will be unnecessary to describe the operation of each, the ports in the valve and valve chamber being suitably arranged for each engine to correspond with the relative positions of the cranks.

Referring now to Figs. 1, 2, 11, 12 and 13, the construction of the valve manifold 12 of the starting device will be understood. Should the engine be at rest and it be desired to start the same, the valve 20 is opened to permit the passage of compressed gaseous products from the storage chamber 13 through the pipe 14 into the manifold 12. As seen in Fig. 11, said gas enters the manifold chamber 63 and thence by a port 64 in the wall of the manifold, traverses a port 65 in the valve 25 and finally out through the pipe 15 into the top of cylinder 1, the relative positions of the pistons in the several engines being suitable for the downward movement for the piston in cylinder 1, the gaseous products rush into the cylinder 1 until said piston is forced downwardly. By the time the piston in cylinder 1 has reached the bottom of its stroke, the piston in cylinder 3 has begun its downward stroke at which time (see Fig. 12) the port 66 in the valve 25 will have reached a position in which it opens a passage therethrough to the pipe 17 leading to the top of cylinder 3 thus

forcing the piston downwardly in said cylinder 3. In turn the piston in cylinder 2 is in the same manner forced downwardly by the compressed gas rushing through the port 5 67 into the pipe 16.

Figs. 9 and 10 illustrate an embodiment of the valve mechanism in which the valve 68, which is provided with two ports 69 and 70 is revolved once for every two revolutions of the engine shaft 9. In Fig. 9 is represented the relative positions of the parts in which the inlet chamber 71 is placed in communication with a duct 72 leading to one of the charging cylinders 4 by means of the port 70. During the upward movement of the piston, the valve 68 is rotated into a position in which the port 70 connects the duct 72 with the reservoir 73 from which compression reservoir it passes through the duct 74 into the combustion chamber whenever the admission port is opened.

In Fig. 14 of the drawings is shown an embodiment somewhat similar to the other embodiments with the exception that the ducts 30, 31, 32 and 39, 40 and 41 are eliminated, for which purpose the valve housing is mounted upon the outer wall of the engine casing adjacent the port opening into the combustion cylinders. In this embodiment, 30 the rotary valve 75 is provided with the oppositely disposed ports 76 and 77 registering successively with the port 78 leading to the charging cylinder 4, the port 79 leading to the inlet chamber 80, and with the port 83 leading to the compression reservoir 81, said reservoir 81 communicating directly with the combustion cylinder through the port 82.

While we have specifically described the embodiment of the invention shown in the drawings, we do not wish to be limited to the exact constructions shown therein since it is obvious that various modifications can be embodied without departing from the spirit of our invention.

45 What we claim is—

1. In an internal combustion engine, the combination with a valve housing comprising three chambers, one of said chambers being provided with an inlet port for a gaseous mixture, another of said chambers being adapted to serve as a reservoir for compressed gaseous mixture and the third chamber being provided with ports communicating respectively with the other two chambers and another port independent of said other two chambers, and a valve movable in said third chamber, said valve being provided with passages to place the inlet chamber in communication with the compression chamber of the motor and to place the latter in communication with the reservoir chamber.

2. In an internal combustion engine, the combination with combustion cylinders and means for compressing a gaseous mixture

outside of said cylinders, of a valve housing provided with inlet ports for the gaseous mixture, a second series of ports communicating with said compressing means, and a third series of ports communicating with 70 said combustion cylinders, and a valve movable in said housing, said valve being provided with passages adapting it to connect said inlet ports with said compressing means and subsequently thereto to connect the compressing means successively with each of said combustion chambers.

3. In an internal combustion engine, the combination with combustion cylinders and means for compressing a gaseous mixture, 80 of a valve housing comprising a receiving chamber for a gaseous mixture, a reservoir for compressed gaseous mixture, and a valve chamber, said valve chamber being provided with ports leading respectively to said compressing means, receiving chamber and reservoir, a valve in said valve chamber adapted to connect receiving chamber with said compressing means and said compressing means with the said reservoir, and means 90 for admitting compressed gaseous mixture from said reservoir into said cylinders.

4. In an internal combustion engine, the combination with combustion cylinders, compression cylinders, and pistons movable in 95 said cylinders, of a valve housing comprising a mixture-receiving chamber, a reservoir and a valve chamber, said valve chamber being provided with ports leading to said compression cylinders, receiving chamber and 100 combustion cylinders respectively, a valve in said valve chamber provided with passages whereby said compression chamber may be connected up to the receiving chamber and whereby said compression chamber may be 105 connected up to said reservoir, and means controlled by the piston in the combustion chamber for charging said combustion cylinders from said reservoir.

5. In an internal combustion engine, the 110 combination with combustion cylinders, charging cylinders, and pistons movable in unison in said cylinders, of a valve housing comprising a mixture-receiving chamber, a reservoir and a valve chamber, said valve 115 chamber being provided with ports leading to said charging cylinders, receiving chamber and combustion cylinders respectively, a valve in said valve chamber for controlling said ports, and means driven by said 120 pistons for operating said valve, said means being adapted to move the valve in such manner as to open communication between the charging and combustion chambers every time said pistons reach their outermost position.

6. In an internal combustion engine, the combination with combustion cylinders, charging cylinders, and pistons movable in unison in said cylinders, of a valve housing 130

- comprising a mixture-receiving chamber, a reservoir and a valve chamber, said valve chamber being provided with ports leading to said charging cylinders, receiving chamber and combustion cylinders respectively, a valve in said valve chamber provided with passages whereby said charging chambers may be connected up to the receiving chambers, and whereby said charging chambers 5 may be connected up to said reservoir, means 10 controlled by the pistons in the combustion chambers for charging said combustion chamber from said reservoir, and means operably connecting said valve with said pistons, said means being adapted to open the 15 connection between the receiving chamber and the charging cylinders during the piston movement in one direction and to open the connection between the charging cylinders and reservoir during the piston movement in the opposite direction.
7. In an internal combustion engine, the combination with combustion cylinders and charging cylinders, of a valve housing provided with an inlet port for a gaseous mixture and ports leading respectively to said combustion cylinders and charging cylinders, and a valve in said housing adapted to place an inlet port in communication with 20 a charging cylinder and subsequently during the same cycle to place a charging cylinder into communication with a combustion cylinder.
8. In an internal combustion engine, the combination with combustion and charging cylinders, and a piston in each of said cylinders, said pistons being connected together to move in unison, of a valve housing provided with an inlet port for a gaseous mixture and ports leading respectively to said combustion and charging cylinders, a compression reservoir, a valve in said housing adapted to place the inlet port in communication with a charging cylinder and a charging cylinder in communication with a combustion cylinder through the compression reservoir, and means operably connecting said valve with said pistons to connect a charging cylinder with the inlet port during 40 one portion of its cycle and to connect the charging cylinder with a combustion cylinder through the compression reservoir during another portion of the same cycle.
9. In an internal combustion engine, the combination with a combustion chamber provided with a piston, of means driven by said piston for compressing a gaseous mixture, a storage chamber for combustion products connected to said combustion chamber, a valve housing provided with an inlet port for the gaseous mixture, ports leading to said compressing means and combustion cylinder respectively, a port leading to said storage chamber, and a second port leading to said combustion chamber, and a

valve movable in said housing, said valve being adapted to connect the storage chamber port with the second port leading to the combustion chamber to start the engine, to connect the compressing means with said inlet port, and to connect said compressing means with said combustion chamber. 70

10. In an internal combustion engine, the combination with a combustion chamber provided with a piston, of means driven by said piston for compressing a gaseous mixture, a storage chamber for combustion products connected to the top of said combustion chamber, a valve housing provided with ports leading to said compressing means and combustion chamber and with further ports leading to said storage chamber and the top of the combustion chamber, a common valve for controlling all of said ports, said valve being adapted to start the engine by the gases in said storage chamber and to operate the engine by transferring gases from said compressing means to said combustion chamber, and means driven by said piston for operating said valve. 75 80 85 90

11. In an internal combustion engine, the combination with a plurality of combustion cylinders arranged in a series, means other than said cylinders for compressing a gaseous mixture, a valve housing provided with an inlet port for each of said cylinders, a second port leading to the compressing means, and a third port leading to each cylinder, a valve for controlling the ports of all of said cylinders whereby during the successive explosions in the engines, the inlet port for each engine is connected up with the compressing means for that engine and the compressing means is connected up with the corresponding combustion cylinder. 95 100 105

12. In an internal combustion engine, the combination of a plurality of combustion cylinders, compressing and charging cylinders therefor, a valve housing common to all cylinders, said housing comprising a mixture-receiving chamber, a reservoir for compressed mixture, and a valve chamber, a valve in said valve chamber, said valve chamber and valve being provided with cooperating ports for connecting said compressing and charging cylinder with said receiving chamber and reservoir successively, means for conveying the compressed mixture from the reservoir to each cylinder, and a piston in each combustion cylinder adapted to automatically control the admission of mixture to that cylinder. 110 115 120

13. In an internal combustion engine, the combination of a plurality of combustion cylinders, compressing and charging cylinders therefor, a storage reservoir for combustion products connected to the upper end of one of said cylinders, a valve housing common to all of said cylinders, said housing comprising a mixture-receiving cham- 125 130

ber, a reservoir for compressed mixture and a valve chamber, a manifold chamber connected with said valve housing and communicating therewith by a port for each 5 combustion chamber, a valve in said valve chamber, said valve chamber and valve being provided with coöperating ports for connecting each charging cylinder with said receiving chamber and reservoir success- 10ively, and said valve and manifold chamber being provided with additional coöperating ports for connecting the storage reservoir with successive combustion cylinders, means for conveying the compressed mix- 15ture from the reservoir to each cylinder, and a piston in each combustion cylinder adapted to automatically control the admission of mixture to that cylinder.

14. In an internal combustion engine, the 20 combination of combustion cylinders, compression and charging cylinders therefor, a storage tank for combustion products connected to the upper end of one combustion cylinder, a check valve between the cylinder or cylinders and tank, a manifold connected up with said tank and the top of each 25 of said cylinders, and a common valve for controlling the flow of gaseous mixtures be-

tween the charging and combustion cylinders and for controlling the flow of combustion products from said tank to each of said cylinders. 30

15. In an internal combustion engine, the combination of combustion cylinders, compression and charging cylinders therefor, a 35 storage tank for combustion products connected to the upper end of one combustion cylinder, a check valve between the cylinder and tank, a manifold connected up with said tank and the top of each of said cylinders, 40 a common valve for controlling the flow of gaseous mixtures between the charging and combustion cylinders and for controlling the flow of combustion products from said tank to each of said cylinders, and a valve inter- 45 posed between said tank and manifold.

In testimony whereof we have signed our names to this specification, in the presence of two subscribing witnesses, on this 14th day of March A. D. 1910.

RICHARD H. MORROW.
JAMES MORROW.
